LOUVERED FLUORESCENT LIGHTING FIXTURE

Donald C. McCormack, Toronto, Ontario, Canada, assignor to J. A. Wilson Lighting & Display Ltd., Toronto, Ontario, Canada, a corporation

Application July 21, 1955, Serial No. 37,077

Term of patent 14 years

(Cl. D48—23)

Fig. 1 is a perspective view of a louvered fluorescent lighting fixture showing my new design; and

Fig. 2 is a sectional view thereof to a larger scale, taken on a vertical plane through the line 2—2 of Fig. 1.

I claim:

The ornamental design for a louvered fluorescent lighting fixture, as shown.
